COMPACT

Roman Adler, New York, N. Y.

Application September 17, 1946, Serial No. 697,425

4 Claims. (Cl. 132—83)

1

The invention relates to ladies compacts, and more particularly to light-equipped compacts.

It is the primary object of the present invention to provide a compact which has readily accessible compartments for the reception of different cosmetics as well as illumination equipment, and which in the dark may be made to illuminate the user's face to best advantage for the application of the various cosmetics.

It is another object of the present invention to provide a compact which, while sturdy in construction and pleasant in appearance, is made from simple parts that are readily assembled without requiring any special skill, so that the compact lends itself to rapid and inexpensive mass production.

The above and other objects, features and advantages of the present invention will be fully understood from the following description, considered in connection with the accompanying illustrative drawings.

In the drawings:

Fig. 1 is a perspective view of a closed compact embodying the present invention;

Fig. 2 is another perspective view of the same compact when open;

Fig. 3 is a cross section through the compact;

Fig. 4 is a section taken substantially on the line 4—4 of Fig. 3; and

Fig. 5 is a section taken substantially on the line 5—5 of Fig. 2.

Referring to the drawings, the reference numeral 10 designates a compact which comprises a base receptacle 12 and a cover 14 therefor. The receptacle 12 is, in the present instance, of square shape but may be round or of any other suitable shape and may be made from any suitable material, preferably metal. The front wall 50 of the receptacle 12 is lower than the remaining walls of the latter for a purpose described hereinafter. The receptacle 12 and the cover 14 are provided with preferably integral hinge portions 16 and 18, respectively, through which extends a pin 20 (Fig. 2) for hingedly connecting the cover 14 with the receptacle 12. The cover 14 has suitably secured thereto a spring latch 28 having a hole 30 for snapping over a pin 32 on the receptacle 12 in order to lock the cover 14 in its closed position. The spring latch 28 is bent outwardly at 33 so as to afford a convenient grip for the user to release the latch from the pin 32 and open the compact.

Suitably secured to the bottom 34 of the receptacle 12 is a circular upright partition 36 (Figs. 3 and 4) which divides said receptacle into a

central compartment 38 for the reception of face powder or any other cosmetic, and a surrounding compartment 40 for the reception of illumination equipment to be described hereinafter.

Another cover 25 is hinged to the top of the receptacle 12, and is to this end provided with spaced hinge portions 46 (Fig. 2), which fit between the adjacent hinge portions 16 and 18 of the receptacle 12 and cover 14, respectively, and receive the pin 20 which passes through the hinge portions 16 and 18. The cover 25 serves as a closure for the compartment 40 which houses the illumination equipment, and is centrally apertured and turned inwardly as at 45 (Fig. 3) to fit around the top of the partition 36 and expose the powder compartment 38. The cover 25 has a depending wall 47 (Figs. 2, 3 and 5) which is complementary to the front wall 50 of the receptacle 12 and continues the same to the top of the latter when said cover is closed. The cover 25 may be opened for access to the illumination equipment in the compartment 40 for the repair or replacement of parts.

Suitably secured to the cover 25 are corner elements 22 which are preferably, but not necessarily, triangular in shape, as shown in Figs. 1 and 2. The cover 14 is shaped to fit between the corner elements 22 when closed (Fig. 1), in which position the diverging side flanges 24 of said cover 14 rests on top of the other cover while the parallel side flanges 26 of the cover 14 straddle the adjacent sides of the receptacle 12. When the cover 14 is closed, the same is flush with the corner elements 22, as shown in Fig. 1. The depending wall 47 of the cover 25 has adjacent each corner element 22 an offset, downwardly extending tab 37 (Fig. 5) which fits behind the front wall 50 of the receptacle 12 and has a projection 39 that snaps into a hole 51 in the front wall of said receptacle when the cover 25 is closed.

The apertured cover 25 is provided with a notch 52 (Fig. 3) which is to receive a laterally projecting tongue 54 of another cover 56 for the powder compartment 38; said cover 56 being furthermore dish-shaped to provide a receptacle 57 for a powder puff or pad (not shown). The tongue 54 on the cover 56 is held in the notch 52 by the adjacent top edge 60 of the partition 36 on which said tongue 54 normally rests. The cover 56 is thus removably mounted in the compact for swinging movement to and from closing position, as will be readily understood. The cover 56 is also provided with a latch 62 which is adapted to snap into an aperture 64 in the cover 25 when the cover 56 is closed, thus

releasably locking the cover 56 in closed position.

The cover 56 is provided in its bottom 66 with a central depression 68 which serves as a receptacle for a cosmetic preparation, such as rouge in cake form, for instance. Suitably hinged at 69 to the cover 56 is a lid 70 which may be swung open or closed.

The cover 14 carries on its inner face a mirror or reflector 78 which is preferably made of metal and has a highly polished reflector surface. The reflector 78 is removably attached to the cover 14 by means of a pin 80 (Fig. 3) which projects from the cover 14 and extends through a hole 82 in the reflector, and a retainer spring 84 which overlies the reflector 78 and is yieldingly held in the cover 14.

The cover 14, which is preferably of metal, may be lined on its outer surface with any suitable decorative material, such as a plastic plate 92 of any desired color, for instance. If desired, the outer lining 92 of the cover 14 may be provided with raised ornaments, such as a crescent 94 and a star 96, for instance.

The illumination equipment in compartment 40 comprises several flash light batteries 100 (Fig. 4) which are preferably of the size of pencil-type batteries, and light bulbs 102 which are energized by the batteries 100. The batteries 100 are separately removably mounted in suitable brackets 104 for ready replacement, while the light bulbs 102 are mounted in conventional sockets 106 (see also Fig. 5). In order to complete an electric circuit through each light bulb 102, there is provided a manually operable switch 110 (Fig. 4), having a fixed contact element 111 and a movable contact element 112 which is turned by a knob 114 on the outside of the receptacle 12. The movable contact element 112 is grounded to the metallic receptacle 12. The fixed contact element 111 is insulated from the receptacle 12 and connected with the adjacent batteries 100a and 100b. The other two batteries 100c and 100d are connected in series with the batteries 100a and 100b, respectively, and each pair of series-connected batteries is connected with a socket 106. The fixed contact 111 of switch 110, the mounting brackets 104 for the batteries 100 and the sockets 106 for the light bulbs 102 are insulated from the metallic receptacle 12 and mounted in any suitable manner on an insulating lining 120 on the bottom of the receptacle 12. Each light bulb 102 is grounded at 122 to the metallic receptacle 12 (Fig. 5), so that the circuits through the light bulbs 102 are closed when the contact members 111 and 112 are engaged, and open when said contact members are disengaged, as will be readily understood. Each light bulb 102 extends through an aperture 130 in the cover 25 and into an aperture 132 in a corner element 22 (Fig. 5) which may be of any transparent or translucent material, such as plastic. The corner elements 22 may, if desired, be adorned in any suitable way, for example with ornaments 136 in the shape of stars similar to the star ornament 96 on the cover 14 (Fig. 1), so that the light from the bulbs 102 passes through the central apertures 138 of the star ornaments 136 (Fig. 5).

The receptacle 12 may also be provided with an

inwardly formed shell 140 for the reception of a lipstick container (not shown) having a handle 142 (Fig. 2).

It will be understood that various changes in the details of construction and the arrangement of parts may be made without departing from the underlying idea or principles of this invention within the scope of the appended claims.

Having thus described my invention, what I claim and desire to secure by Letters Patent is:

1. In a compact, the combination of a receptacle open at its top and having an upright partition projecting from its bottom and dividing the receptacle into an inner compartment and a surrounding outer compartment, each compartment being open at the top, two superposed covers for said receptacle and said outer compartment, respectively, said covers being hinged to said receptacle and independently turnable to and from closing position, and a lid for said inner compartment hinged on the cover for said outer compartment and being dish-shaped to serve as a receptacle.

2. The combination in a compact as set forth in claim 1, in which said dish-shaped lid has a further depression in its bottom to serve as another receptacle, and which further comprises another lid for said other receptacle hinged to the first mentioned lid.

3. In a compact, a receptacle having compartments open and closed, respectively, at the top of the receptacle, electrical illumination means including a light bulb in said closed compartment, the latter having a window at the top of said receptacle adjacent said light bulb for the passage of light from the latter to the outside of said receptacle, a cover over the top of said receptacle hinged to the latter, said cover being cut away so as to terminate short of said window when in closed position, a mirror on the inner surface of said cover, and a filler piece on the top of said receptacle having an opening exposing said window and fitting the cut-away portion of said cover and being flush with the latter when closed.

4. In a compact, a receptacle having an apertured top, electrical illumination means in said receptacle including light bulbs on opposite sides of said receptacle and outside the confines of the aperture in the top thereof, said top having further apertures adjacent said bulbs, respectively, for the passage of light from the latter to the outside of said receptacle, a cover over the top of said receptacle hinged to the latter for turning movement about an axis parallel to a line passing through said bulbs, and a mirror on the inner face of said cover.

ROMAN ADLER.
